UNITED STATES PATENT OFFICE.

RUFUS A. SIMPSON, OF OAKLAND, CALIFORNIA.

BUTTER-CUTTING MACHINE.

1,329,810.

Specification of Letters Patent.

Patented Feb. 3, 1920.

Application filed May 23, 1918. Serial No. 237,633.

To all whom it may concern:

Be it known that I, RUFUS A. SIMPSON, a citizen of the United States, residing at Oakland, in the county of Alameda and 5 State of California, have invented certain new and useful Improvements in Butter-Cutting Machines, of which the following is a specification.

This invention relates to improvements 10 in butter cutting machines and more particularly to a machine of the type illustrated in Patent #1,236,219 which was issued to me on August 7, 1917.

In machines of this character the cutting 15 head is moved longitudinally of a block of butter, the head being provided with crossed wires for cutting the butter into squares. In use, considerable effort is required to force these wires through the cube of hard 20 butter and my present invention has as its principal object the providing of means for more effectively moving the cutting head. With this improved means the head is moved forward when cutting at a reduced 25 gear ratio and when not cutting is moved at a higher gear ratio.

A further object of my invention is to provide a two speed device which is simple in construction, which contains no inac- 30 cessible parts and which effectively accom- plishes the above specified objects.

With these and other objects in view, the invention consists of certain novel features of construction, combinations and arrangements of parts hereinafter described and more specifically pointed out in the ap- 35 pended claims; it being understood that changes in form, proportion, size and minor details of construction within the scope of 40 the claims may be resorted to without de- parting from the spirit of the invention or sacrificing any of the advantages thereof.

Referring to the drawing forming a part 45 of this specification.

Figure 1— is a view in side elevation of a butter cutter having my improved invention applied thereto.

Fig. 2— is a view in section on the line 2—2, Fig. 1.

Fig. 3— is a view in horizontal section through the improved gear means for driv- 50 ing the cutter-head.

Referring to corresponding parts of the several views by the same numerals of ref-

erence, the butter cutter comprises a frame 55 having the longitudinal side member 1 sup- ported on suitable legs 2 and to which are attached angles 3.

The cutter-head denoted generally by 4 comprises a frame 6 containing crossed 60 wires 6' for cutting the butter into squares and a vertically movable wire 7 for sep- arating the squares from the cube of uncut butter. Back of this cutter-head is a tilt- 65 ing frame 8 on which the cut butter is re- ceived before carrying it away for wrapping.

The cutter-head above mentioned is at- tached to angles 5 which lie just inside of angles 3 and parallel thereto. Attached to the upper surfaces of angles 5 are journals 70 10 in which are non-revolubly mounted a sleeve 11. The frame 8 is tiltable on this sleeve so that the receiving frame and cutter-head are tied together by the angles 5.

Extending longitudinally along the up- 75 per surfaces of angles 3 are rack bars 14 which are provided with the undercut re- cesses 15. Engaging the edge of the rack bar above this recess is a grooved extension 16 on the side of the journals 10. This ex- 80 tension, together with similar members on the forward end of the cutter-head, serves as supports and guides for the longitudinally movable parts.

Revolubly mounted in sleeve 11 is a shaft 85 12 which is provided with toothed gears 13 that mesh with the teeth of rack bars 14. Thus when shaft 12 is rotated, the angles 5 and associated parts will be moved longi- 90 tudinally on the frame.

Shaft 12 is driven by the double ended 95 crank 32 either directly coupled or at re- duced speed through the planetary mecha- nism shown in Figs. 1 and 3. This mecha- nism consists of an annulus 16' having the 100 internal gear teeth 17 and a laterally ex- tends arm 40 which engages a pin 41 pro- jecting from the cutter-head. Back of the annulus 16' is a ring 18 which is connected thereto by means of arms 19. Engaging this 105 ring is a disk 20 from the rear face of which extends a flange 20' that contacts with the inner circumferential surface of ring 18. Extending from the forward face are pins 21 or stub shafts on which are revolvably 110 mounted the toothed gears 22, these gears 115 mounted the gear teeth 17.

The disk 20 is revolvably mounted on the

ring 18 and is held thereon by means of nuts 23 which have extension flanges that engage the outer surface of the ring. The disk is provided with a hub 25 which is keyed, pinned or otherwise attached to shaft 12.

Engaging the toothed gears 22 is a pinion 30 which is axially movable on shaft 12 and is provided with the forwardly extending hub 31. Extending from the opposite sides of this hub are arms which form a double ended crank 32 on the outer ends of which are mounted suitable operating handles 33. The hub 31 is provided with the T-shaped slot 34 which is adapted to engage a pin 35 in the outer end of shaft 12. This pin is so positioned that when the hub is moved until the bottom of the slot engages the pin, then the pinion 30 has moved such a distance that its teeth are disengaged from the teeth of gears 22.

In operation a cube of butter 45 is placed on the receiving table 46 the rear portion being held by the stationary blocks 47. The butter-head is then moved forward by means of the planetary gearing just described, the rotation of the handles 33 causing the pinion 30 to rotate the gears 22, and thus the disk 20 which is keyed to shaft 12. The rotation of shaft 12 through gears 13 acting on the rack bars, moves the cutter-head forward and forces the cross wires through the butter cube. When the end of the cut portion contacts with the vertical surfaces of the receiving table 8 the vertical cutting wire 7 is operated by means of the lever arms 48. The cut butter is then removed and a new receiving frame substituted and the head again advanced until the entire mass of butter is cut into squares of a predetermined size.

It will be apparent that considerable effort is required to force the cross wires through the mass of hard butter and that for ease of operation a comparatively low gear ratio must be employed between the operating crank and the drive shaft 12. This reduction is accomplished by the planetary system above described. On the other hand, when moving the cutting-head away from the stationary end blocks 47, little effort is required and in order to effect a quick return I provide a direct drive between the cranks and the drive shaft. This drive is thrown into operation by shifting pinion 30 on shaft 12 whereby it is disengaged from the gears 22 and the slot 34 is engaged on pin 35. Thus when the cranks are turned the shaft is turned at the same speed, giving a much quicker movement to the cutting-head.

Having thus described my invention, I claim as new and wish to cover by Letters Patent:—

1. A butter cutter comprising in combination with a frame and a cutter-head slidably mounted thereon, toothed rack bars at-

tached to said frame, a drive shaft movable with said cutter-head, toothed pinions attached to said shaft and engaging said rack bars, a planetary gear system for driving said shaft at low speed, an operating crank, and means whereby said crank may be operatively engaged either with said planetary system or said shaft.

2. A butter cutter comprising in combination with a frame and a cutter-head slidably mounted thereon, toothed rack bars attached to said frame, a drive shaft movable with said cutter-head, toothed pinions attached to said shaft and engaging said rack bars, a planetary gear system comprising a non-rotatably mounted, internally toothed gear, a disk attached to said shaft, a concentric toothed pinion revolvably mounted on said shaft, intermediate gears revolvably mounted on said disk and adapted to engage said pinion and said internal gear, a driving crank slidably mounted on said shaft, and means whereby said crank may be operatively engaged with either said shaft or said planetary system.

3. A butter cutter comprising in combination with a movable cutter-head, a drive shaft for said head, a planetary gear system comprising a non-rotatably mounted, internally toothed gear concentric with said shaft, a disk attached to said shaft, toothed gears revolvably mounted on said disk and meshing with said internal gear, an operating crank slidably mounted on said shaft, and having an inner and outer operative position, a toothed pinion carried by said crank adapted to mesh with said gears when said crank is in its inner position, and clutch means for engaging said crank with said shaft when said crank is in its outer position.

4. A butter cutter comprising in combination with a movable cutter-head, a drive shaft therefor, a planetary gear system comprising a non-rotatable annulus having an internally toothed gear, a disk attached to said shaft, intermediate gears revolvably mounted on said disk and meshing with said internal gear, a driving pinion adapted to mesh with said intermediate gears, clutch means carried by said shaft, and a driving crank slidably mounted on said shaft so that it may engage either said planetary system or said clutch means.

5. In a driving mechanism for butter cutters comprising a revoluble driving shaft, an internal non-rotatable toothed gear, a disk revoluble with said shaft, intermediate toothed gears revolvably mounted on said disk, an operating member and means carried by said member operatively connecting it to said shaft at times and other means for operatively connecting it to said intermediate gears at other times.

6. In a driving mechanism for butter cut-

ters comprising a revolvably mounted driving shaft, a planetary gear system carried thereby, a driving member, and means whereby said driving member may be operatively connected to said driving shaft at times and to said planetary gear system at other times.

7. A driving machine for butter cutters comprising a movable cutter-head, a revolvably mounted drive shaft therefor, a planetary gear system for said shaft, a driving member, and means whereby said driving member may be selectively connected to

either said planetary gear system or to said shaft. 15

8. A driving mechanism for butter cutters comprising a revolvably mounted driving shaft, a toothed pinion attached thereto, a toothed rack for engagement with said pinion, a planetary gear system carried by 20 said shaft, a driving member and means whereby said driving member may be operatively connected to either said planetary system or to said shaft.

In testimony whereof I affix my signature. 25

RUFUS A. SIMPSON.
